JAR SUPPORTING BRACKET

Filed Jan. 21, 1929

UNITED STATES PATENT OFFICE

LOUIS S. ANDERSON, OF CHICAGO, ILLINOIS, ASSIGNOR TO REID, MURDOCH & COMPANY,
OF CHICAGO, ILLINOIS, A CORPORATION OF ILLINOIS

JAR-SUPPORTING BRACKET

Application filed January 21, 1929. Serial No. 333,761.

The invention relates generally to brackets for use in supporting jars or similar receptacles in front of shelves. More particularly the invention relates to that type of jar supporting bracket which comprises an elongated plate which has a ring-shaped strip connected to one of its ends to form therewith an open top socket for receiving the lower end of the jar, and embodies means at its other end whereby it may be secured in place on the top face of the shelf and so that the ring-shaped strip is located or positioned in front of the shelf.

One object of the present invention is to provide a bracket of this character in which the ring-shaped strip is formed separately from the other parts of the bracket and the side portions thereof, that is, the portions adjacent the side edges of the plate, are free or disconnected with respect to said plate so that they may be deflected or bent towards each other for the purpose of frictionally engaging or gripping the side wall of the receptacle.

Another object of the invention is to provide a jar supporting bracket of the aforementioned type in which the central and end parts of the ring-shaped strip embody integral right angle attaching tongues and provision is made whereby the tongues on the end parts of the strip are adjustably connected to the plate so that they may be moved to and from each other to vary the diameter of the socket and consequently adapt the bracket for use with receptacles or jars that vary in diameter.

A further object of the invention is to provide a bracket for supporting and displaying a jar, which is generally of new and improved construction and is capable of being manufactured at a comparatively low cost.

A still further object of the invention is to provide a jar support which is an improvement upon that disclosed in Letters Patent

of the United States No. 1,720,876, granted to me July 16, 1929.

Other objects of the invention and the various advantages and characteristics of the present bracket construction will be apparent from a consideration of the following detailed description.

The invention consists in the several novel features herein set forth and more particularly defined by the claims at the conclusion hereof.

In the drawing which accompanies and forms a part of this specification or disclosure and in which like numerals of reference denote corresponding parts throughout the several views:

Figure 1 is a perspective of a bracket embodying the invention;

Figure 2 is a perspective of the ring-shaped strip, disclosing in detail the construction and arrangement of the tongues whereby the strip is attached to the plate;

Figure 3 is a perspective of the plate;

Figure 4 is a vertical longitudinal sectional view illustrating the manner in which the bracket is secured to and supported from the shelf with which it is associated; and

Figure 5 is a plan view made on a small scale and for the purpose of showing the manner in which the ends of the ring-shaped strip are adjustably connected to the plate so that they may be positioned the proper distance apart to form a socket of the desired diameter.

The bracket which forms the subject matter of this invention is adapted primarily to support a substantially cylindrical jar *j* in front of a shelf *s*. It is contemplated that the jar be of glass and for use in displaying the contents of cans on the shelf *s*. The bracket comprises an elongated substantially flat sheet metal plate *6* and a strip *7* which is bent to form a ring or annulus and is mounted on the front end of the plate to form therewith a socket into which the bottom of the jar *j*

snugly fits and by which said jar is securely held against accidental displacement. The rear end of the plate is adapted to fit against the top face of the shelf and to be positioned so that the front end which carries the ring-shaped strip 7 extends in front of the shelf, as shown in Figure 4. The plate is held in its operative position by nails or screws 8 which pass through circular holes or apertures 9 punched in the rear end of the plate. The central or intermediate portion of the plate has cut therein a U-shaped slit 10 which operates to form an elongated member 11. The latter is connected to the front end of the plate 6 and is bent so that its connected end extends downwardly at an acute angle and the distal end thereof projects rearwardly and is substantially parallel to the plate. The angled connected end of the member 11 is deflected centrally for reinforcing purposes and operates to form a brace whereby the front or outer end of the plate is supported from below. The distal end of the member is adapted to lap or fit against the bottom face of the shelf *s* and is secured in place by nails or screws 12. The latter pass through circular holes 13 which are punched in the horizontally extending part of the member 11. A characteristic of forming the brace member of the bracket in the manner set forth is that the bracket may be applied to shelves of different thicknesses simply by deflecting or bending the tongue into the proper position.

The strip 7, like the plate 6, is formed of sheet metal. It is made separately from the plate and embodies adjacent the medial portion thereof an inwardly extending tongue 14. This tongue is formed integrally with the bottom edge or marginal portion of the strip and is bent so as to extend at substantially right angles. It fits against the top face of the plate and is positioned adjacent the longitudinal center and front edge of said plate. A rivet 15 extends upwardly through a hole 16 in the front end of the plate 6 and a hole 17 in the tongue and is beaded over to secure said tongue fixedly in place. By forming and attaching the tongue 14 as specified, both the inner and the outer peripheral surfaces of the strip 7 are independent of any attaching means whatsoever. This is of particular advantage in that there are no obstructions to be encountered by the receptacle or jar *j* when the latter is inserted into the socket 55 and the outer periphery is smooth and adapted for the ready application of advertising material. The ends of the strip form retaining means for the back of the jar and are each provided with an inwardly extending tongue 18 which like the tongue 14, is formed integrally with the bottom edge or marginal part of the strip. The tongues 18 are bent to extend at substantially right angles and fit against the top face of the plate. They are positioned adjacent the central part of the

plate between the side edges and the slit 10 and are secured fixedly in place by rivets 19. These rivets pass through circular apertures 20 and 21 which are punched in the tongues 18 and the plate 6 respectively, and are beaded over to effect a substantially permanent attachment. In addition to the apertures 21 in the plate, there are apertures 22 and 23. These last mentioned apertures are punched in the plate so as to be positioned adjacent the apertures 21 and to form therewith two series of holes. As a result of this plate construction it is possible during the fabrication of the bracket to secure the ends of the strip 7 either in close proximity to each other to form a socket of a relatively small diameter or in spaced relation, as shown in dotted lines in Figure 5, to form a socket of comparatively large diameter. When the tongues 18 are arranged so that the apertures 20 register with the apertures 23, the socket is of maximum diameter and consequently adapted to receive a jar of large size. When the apertures 20 of the tongues are placed in registry with the apertures 22, the jar socket is of intermediate dimensions. By having but three attaching tongues on the strip 7 and securing them in the manner set forth, the sides of said strip which project outwardly of the side edges of the plate, are free or disconnected with respect to the plate and may be deflected or bent towards each other so as to engage or grip frictionally the sides of the jar. The front end of the plate 6 is cut so that the front edge is curved to conform substantially to the curvature of the medial portion of the strip 7.

The bracket is applied by sliding it laterally into engagement with the shelf *s* and so that the top face of said shelf is lapped by the rear end of the plate 6 and the bottom face is lapped by the horizontal portion of the member 11. The bracket is rigidly secured in place by driving the nails or screws 8 and 12 through their respective apertures 9 and 13 and into the shelf. In this position of the bracket the end bearing the ring-shaped strip is located outwardly or in front of the shelf with the result that the jar *j* is prominently displayed. In the event that the socket should prove to be too small for the jar or it should be desired to use a larger jar with the bracket, the rivets 19 may be withdrawn and the ends of the strip 7 shifted apart and reattached in the desired position.

The jar supporting bracket herein shown and described consists essentially of but two sheet metal parts and consequently may be produced at a low cost. It is efficient in operation and serves to hold effectively the jar against accidental displacement.

The invention is not to be understood as restricted to the details set forth, since these may be modified within the scope of the ap-

pended claims, without departing from the spirit and scope of the invention.

Having thus described the invention, what I claim as new and desire to secure by Letters Patent, is:

1. A bracket for supporting and displaying a jar or similar receptacle in front of a shelf, consisting of an elongated substantially flat plate having one end thereof adapted to fit on the top face of the shelf and provided with means whereby it may be secured to the shelf in such position that the other end of the plate projects outwardly from said shelf, a strip bent to form a substantially complete ring, said strip being positioned over the said other end of the plate to form therewith a socket for receiving the bottom of the jar, and means whereby the medial and end portions of the strip are fixedly connected to the front and central parts of the plate respectively, the side portions of the strip being disconnected with respect to the sides of the plate so that they may be distorted by bending to engage yieldingly the side wall of the jar.

2. A bracket for supporting and displaying a jar or similar receptacle in front of a shelf, said bracket consisting of an elongated substantially flat plate having one end thereof provided with means whereby it may be secured to the shelf in such position that the other end of the plate projects outwardly from said shelf, a strip bent to form a substantially complete ring and positioned over the said other end of the plate to form therewith a cylindrical socket for receiving the bottom of the jar, connecting means between the medial portion of the strip and the front end of the plate, and means for connecting the ends of the strip to the central part of the plate at different distances apart, so that the bracket may be constructed for use with jars that vary in diameter comprising tongues on the strip-ends and connecting elements associated with the tongues and cooperating with series of apertures in the central part of the plate.

3. A bracket for supporting and displaying a jar or similar receptacle in front of a shelf, said bracket consisting of a one-piece substantially flat sheet metal plate adapted to be positioned horizontally and having one end thereof adapted to fit on the top face of the shelf and provided with means whereby it may be secured to the shelf in such position that the other end of the plate projects outwardly from said shelf, the central part of the plate being slit to form a brace member said brace member being bent to extend downwardly and then rearwardly to lap the bottom face of the shelf, a strip bent to form a substantially complete ring and positioned over the said other end of the plate to form therewith a cylindrical socket for receiving the bottom of the jar, connecting means between

the medial portion of the strip and the front end of the plate, and means for connecting the ends of the strip to the central part of the plate at different distances apart so that the bracket may be constructed for use with jars that vary in diameter comprising tongues on the strip-ends and connecting elements associated with the tongues and cooperating with series of apertures in the plate adjacent the slit part.

Signed at Chicago, Illinois, this 17th day of January, 1929.

LOUIS S. ANDERSON.
